INVENTOR

William Emerson,
BY J. M. Bowen

ATTORNEY.

UNITED STATES PATENT OFFICE.

WILLIAM EMERSON, OF DAVENPORT, NEW YORK.

IRONING-TABLE.

SPECIFICATION forming part of Letters Patent No. 433,936, dated August 12, 1890.

Application filed December 15, 1887. Serial No. 257,958. (No model.)

To all whom it may concern:

Be it known that I, WILLIAM EMERSON, a citizen of the United States, and a resident of Davenport, in the county of Delaware and 5 State of New York, have invented certain new and useful Improvements in Ironing-Tables, of which the following is a specification.

This invention has reference to ironing-tables which are capable of being folded into 10 a compact condition for storage or transportation, and its novel features are pointed out in the claim at the end hereof.

This invention is shown in the accompanying drawings, which form part of this specification, and in which the same parts are indicated by the same reference-figures in the several views.

In the drawings, Figure 1 is a central vertical longitudinal section of a table embodying my improvements. Fig. 2 is a front elevation of the standard 6. Fig. 3 is an elevation of that end of the table to which the legs 17 are attached, and Fig. 4 is an inverted plan view of the table folded.

25 5 represents the top of the table, which may be of the form shown in Fig. 4 or of any other preferred form, and 6 indicates a standard which is provided at its top with a bracket 7 and at its lower end with a foot 8, considerably greater in width than is standard 6, and which is furnished with pins in 30 its bottom, as at 9, to prevent the table from slipping when in use. At the top of the standard there is a dowel 10, which is adapted 35 to enter a hole in the under surface of the top of the table when the table is unfolded.

In the front surface of the foot-piece 8 there is a pin 11, which is adapted to enter a hole 12 in the under surface of the top of the 40 table when the table is folded. The foot 8, which is secured to the front of the bottom of standard 6, is provided with the pins 9, and furnishes a substantial rest for that end of the table, and also serves as a stop to prevent 45 said standard from falling downward between the braces 13 when the folding mechanism is locked to the under surface of top 5 by fastening device 24, so as to hold the parts together more effectually.

50 13 indicates braces which are pivoted to the outer end of the standard 6 by a bolt 14, passing transversely therethrough, and hinged to rung 15, which latter element is pivoted to brackets 16, secured to the under 55 surface of the table. The legs 17 are also

pivoted to the rung 15, and they are provided with strengthening rungs or braces 18 and 19.

20 represents a short brace, which is jointed at about its center, as at 21, and is pivoted to the braces 13, as at 22, and is also hinged to 60 rung 18, as shown.

In attaching the braces 13 to the rung 15 and in securing the short brace 20 to rung 18, I employ metallic loops composed of galvanized iron or tin, which are marked 23. 65 This method of attachment has the advantage of being very cheap, and it is also very effective. The loops 23 are secured in place by rivets or nails of any kind.

When the table is folded, the entire folding 70 mechanism is held against the under surface of the top 5 by the fastening device 24, engaging with the rung 19 near the bottom of legs 17.

While this table is designed, primarily, for 75 ironing purposes, and particularly for use in private houses, it is nevertheless adapted for use as a table or stand for other purposes than ironing, and will be found serviceable in public as well as in private laundries. 80

Having thus described my invention, what I claim as new, and desire to secure by Letters Patent, is—

In a folding ironing-table, the top 5, provided on its under surface at one end with 85 brackets supporting a rung 15 and near the center of said surface with fastening device 24, in combination with legs 17, pivoted to rung 15 and provided with rungs 18 and 19, a pair of braces 13, likewise pivoted to said 90 rung 15 and pivotally connected at their outer ends to standard 6, which is provided with foot 8 and is adapted to fold between said braces 13 and also to support the free end of the table-top, and the jointed brace 95 20 21, pivoted to rung 18 of legs 17 and also to braces 13 at 22, the said supporting mechanism being constructed and arranged to fold snugly against the under surface of the table-top and to be secured in that position 100 by fastening device 24, substantially as set forth.

Signed at Davenport, in the county of Delaware and State of New York, this 20th day of October, A. D. 1887.

WILLIAM EMERSON.
